INTERLOCKING DOOR HINGE

Frank D. Low, Chicago, Ill., assignor to Hotpoint
Inc., a corporation of New York

Application November 23, 1948, Serial No. 61,633

8 Claims. (Cl. 312—315)

1

The present invention relates to washing apparatus, and more particularly to improved dishwashing apparatus of the general character of that disclosed in the co-pending application of Forrest A. Walker, Serial No. 57,448, filed October 30, 1948.

The dishwashing apparatus disclosed in the Walker application mentioned is of the timed washing cycle type that performs automatically and in predetermined sequence given steps including spraying, washing, rinsing and drying of the dishes and other utensils contained therein. This apparatus comprises a cabinet housing a vertically disposed vat including a front opening and a door for closing the opening, the door being mounted for movements between a substantially vertical closed position and a substantially horizontal open position. In this apparatus the door is supported in its open position by the lower lip or ledge of the vat adjacent to the front opening thereinto; whereby the upper end of the door projecting away from the cabinet in its open position exerts a cantilever action upon the ledge of the vat. Moreover in this apparatus a dish-supporting receptacle or rack is provided that is movable into and out of the vat through the front opening over the door in its open position, which rack in its fully withdrawn position is supported entirely by the door in its open position; whereby the cantilever action upon the ledge of the vat is greatly increased, particularly when the rack is fully loaded with dishes or other utensils. In fact, this cantilever action may be sufficiently great to cause the upper end of the door projecting away from the cabinet in its open position to sag to such an extent that there is some interference with ready movements of the rack over the door.

Accordingly, it is a general object of the present invention to provide in washing apparatus of the character described, an improved hinge arrangement for mounting the door for movements between its substantially vertical closed position and its substantially horizontal open position so that there is no substantial sagging of the door in its open position even though it is reasonably heavily loaded.

Another object of the invention is to provide in cabinet apparatus of the front-opening type provided with a door movable between a substantially vertical closed position and a substantially horizontal open position, an improved and simple hinge mechanism for movably mounting the door.

A further object of the invention is to provide 55 the arrows along the line 8—8 in Fig. 6; Fig. 9

2

in cabinet apparatus of the front-opening type provided with a door movable between a substantially vertical closed position and a substantially horizontal open position, an improved and simple hinge mechanism for movably mounting the door, wherein the mechanism is disengageable to accommodate ready and complete removal of the door from the associated doorway in the cabinet when the door occupies an intermediate position with respect to its closed and open positions.

Further features of the invention pertain to the particular arrangement of the elements of the hinge mechanism incorporated in the dishwashing apparatus, whereby the above-outlined and additional operating features thereof are attained.

The invention, both as to its organization and method of operation, together with further objects and advantage thereof, will best be understood by reference to the following specification taken in connection with the accompanying drawings, in which Figure 1 is a front elevational view, partly broken away, of dishwashing apparatus embodying the present invention; Fig. 2 is a side elevational view, partly broken away, of the dishwashing apparatus shown in Fig. 1; Fig. 3 is an enlarged horizontal sectional view, partly broken away, taken through the lower portion of the dishwashing apparatus shown in Figs. 1 and 2, and illustrating the front of the cabinet and the contained vat, as well as the associated door in its open position; Fig. 4 is an enlarged fragmentary vertical sectional view of the right-hand side of the dishwashing apparatus, taken in the direction of the arrows along the line 4—4 in Fig. 3, and illustrating the door in its fully removed position; Fig. 5 is an enlarged fragmentary vertical sectional view of the left-hand side of the dishwashing apparatus, taken in the direction of the arrows along the line 5—5 in Fig. 3, and illustrating the door in its open position; Fig. 6 is a greatly enlarged fragmentary sectional view of the front of the dishwashing apparatus, taken in the direction of the arrows along the line 6—6 in Fig. 3, and presenting a side elevational view of the associated right-hand hinge mechanism and the connecting parts; Fig. 7 is a greatly enlarged top view of the hinge mechanism and the connected parts, taken in the direction of the arrows along the line 7—7 in Fig. 6; Fig. 8 is a greatly enlarged bottom view of the hinge mechanism and the connecting parts, taken in the direction of the arrows along the line 8—8 in Fig. 6; Fig. 9

is a greatly enlarged vertical sectional and rear view of the hinge mechanism and connecting parts, taken in the direction of the arrows along the line 9—9 in Fig. 6; and Fig. 10 is a greatly enlarged front view of the hinge mechanism and the connecting parts, taken in the direction of the arrows along the line 10—10 in Fig. 6.

Referring now to Figs. 1 to 5, inclusive, of the drawings, the dishwashing apparatus 10 there illustrated, and embodying the features of the present invention is of the general character of that disclosed in the previously mentioned Walker application and comprises a cabinet 11 provided with wall structure, including a front wall 12 having an opening 13 formed in the upper central portion thereof. The front wall 12 carries a front panel 14 having an opening 15 formed in the upper central portion thereof, the openings 13 and 15 being arranged in substantial registry. The general outline of the panel 14 conforms to that of the front of the cabinet 11; whereby the top and sides of the panel 14 are disposed substantially flush with the top wall and respective side walls of the cabinet 11. The front wall 12 is rearwardly offset adjacent to the bottom wall of the cabinet in order to define a foot-receiving recess 16 adjacent to the floor supporting the cabinet 11, permitting a person to work close to the front panel 14. Finally, the bottom of the panel 14 is disposed substantially flush with the top wall of the recess 16 lending a finished appearance to the front of the apparatus 10.

The cabinet 11 houses a substantially vertically disposed vat 17 arranged in the upper central portion thereof and secured in place in any suitable manner, not shown. The vat 17 comprises wall structure, including top and bottom walls 18 and 19 and opposed side walls 20 and 21; the top and bottom walls 18 and 19 and the side walls 20 and 21 terminate in a forwardly directed doorway 22 having a front opening 23 arranged in substantial registry with the front openings 13 and 15. More particularly, the doorway 22 comprises a top flange 24 and opposed side flanges 25 and 26, while the bottom wall 19 provides a forwardly directed bottom flange that terminates in an upwardly and outwardly extending ledge or lip 27 disposed between the side flanges 25 and 26. The ledge 27 is directed first upwardly and outwardly and then downwardly terminating adjacent to the front opening 23 of the doorway 22; whereby the upper edge of the ledge 27 is disposed considerably above the bottom wall 19. A substantially centrally disposed sump 28 is formed in the bottom wall 19 and communicates with a downwardly embossed depression or groove 29 formed substantially centrally in the front of the bottom of wall 19 and extending forwardly toward the central portion of the ledge 27. Further, an upstanding inverted substantially U-shaped inwardly embossed vat rib 30 is formed in the top wall 18 and the side walls 20 and 21 at the junction thereof with top flange 24 and the side flanges 25 and 26, the vat rib 30 including opposed legs 31 and 32 terminating just above the bottom wall 19 and well behind and below the ledge 27.

The cabinet 11 is provided with a front door 33 that comprises an outer body sheet 34 terminating in an inverted substantially U-shaped rearwardly directed marginal flange 35, and an inner body sheet 36 terminating in an inverted substantially U-shaped rearwardly directed marginal flange 37. The inner body sheet 36 is arranged in nested relation within the outer body

sheet 34 and suitably secured in place so that the principal portions of the body sheets 34 and 36 are arranged in upwardly approaching spaced-apart relation. More particularly, the upper portions of the body sheets 34 and 36 are arranged in contacting relation, while the lower edges thereof are arranged in considerably spaced-apart relation defining a wedge-shaped space 38 therebetween; also the inner body sheet 36 carries on the outer surface thereof an outwardly and upwardly projecting bracing sheet 39 contacting the inner surface of the outer body sheet 34 in order to retain the body sheets 34 and 36 in proper spaced-apart relation. The outer body sheet 34 carries a substantially centrally disposed handle 40 positioned adjacent to the upper edge thereof and readily accessible from the exterior. The lower edge of the outer body sheet 34 terminates in a rearwardly offset laterally extending groove 41 that cooperates with an inwardly directed laterally extending edge 42 carried by the panel 14 adjacent to the bottom of the opening 15 formed therein, the groove 41 and the edge 42 cooperating to give the cabinet 11 a finished appearance when the door 33 occupies its closed position.

The door 33 is arranged within the doorway 22 and mounted for pivotal movements with respect to the front opening 15 between a substantially vertical closed position and a substantially horizontal open position by an arrangement including two laterally spaced-apart hinge mechanisms 51 and 52 arranged in the doorway 22. More particularly, when the door 33 occupies its closed position the outer body sheet 34 is disposed in a substantially vertical position and is arranged substantially flush with the front of the panel 14, the central portion of the door 33 projecting slightly forwardly with respect to the panel 14; while the inner body sheet 36 is disposed in an upwardly and forwardly inclined position. On the other hand, when the door 33 occupies its open position the inner body sheet 36 is disposed in a substantially horizontal position and the outer body sheet 34 is disposed in an upwardly and forwardly inclined position. This arrangement is very advantageous as the door 33 may be moved between its open and closed positions through an angle somewhat less than ninety degrees.

Preferably the hinge mechanisms 51 and 52 are identical. More particularly, the right hand hinge mechanism 51 comprises a first fixed substantially U-shaped hinge element 53 including a base 54 and two upwardly directed and laterally spaced-apart arms 55 and 56, and a second movable substantially U-shaped hinge element 57 including a base 58 and two forwardly directed and laterally spaced-apart arms 59 and 60. The base 54 of the hinge element 53 is secured to the bottom wall 19 of the vat 17 rearwardly of and below the ledge 27; while the base 58 of the hinge element 57 is secured to the front surface of the inner body sheet 36 and spaced rearwardly from the rear surface of the outer body sheet 34, whereby the second hinge element 57 is arranged in the wedge-shaped space 38 disposed between the body sheets 34 and 36 of the door 33. Also the hinge mechanism 51 comprises a substantially U-shaped bumper member 61 including a base 62 and two downwardly directed and laterally spaced-apart arms 63 and 64. The base 62 of the bumper member 61 is secured to the bottom wall 19 of the vat 17 below and rearwardly of the ledge 27.

More particularly, a resilient gasket or pad 55 formed of sheet rubber, or the like, is positioned between the upper surface of the bottom wall 19 and the base 54 of the first hinge element 53; and a resilient gasket or pad 66 formed of sheet rubber, or the like, is positioned between the lower surface of the bottom wall 19 and the base 62 of the bumper member 61; and these elements are securely retained in assembled relation by an arrangement including two longitudinally spaced-apart rivets 67, or the like, extending through aligned openings formed in the bottom wall 19, the gaskets 55 and 66 and the bases 54 and 62. The gasket 65 renders the interior of the vat 17 water tight adjacent to the openings through which the rivets 67 extend and resiliently mounts the first hinge element 53 upon the bottom wall 19; while the gasket 66 resiliently mounts the bumper member 61 on the bottom wall 19.

Also the first hinge element 53 comprises a substantially cylindrical pintle 68 extending laterally between the arms 55 and 56 rigidly secured into aligned openings formed therein; while the second hinge element 57 comprises a rearwardly opening saddle 69 carried by the rear end thereof and adapted to engage the pintle 68. More specifically, the rear end of the base 58 terminates in the rearwardly opening saddle 69 that includes an upper part 71 and a lower part 72 disposed in vertically spaced-apart relation. Further, a substantially Z-shaped reinforcing piece 73 extends between the lower rear surface of the base 58 and the lower part 72 in order to render the saddle 69 of strong and rigid construction.

Further, the second hinge element 57 comprises two laterally spaced-apart and downwardly extending tabs 74 and 75 disposed adjacent to the saddle 69 and rearwardly of the ledge 27 when the saddle 69 is in engagement with the pintle 68. The two tabs 74 and 75 have aligned openings therein into which a laterally extending locking pin 76 is rigidly secured; the opposite ends of the locking pin 76 cooperating with two arcuately disposed locking slots 77 and 78 respectively formed in the upper edges of the two arms 55 and 56 of the first hinge element 53, for a purpose more fully explained hereinafter.

A first substantially U-shaped laterally extending abutment 79 is arranged between the arms 63 and 64 adjacent to the lower front edges thereof and suitably secured in place by welding, or the like. The two arms 59 and 60 carried by the second hinge element 57 extend downwardly and rearwardly with respect to the ledge 27, whereby a pair of laterally spaced-apart and arcuately disposed aligned slots 80 and 81 are formed in the structure of the second hinge element 57 and respectively positioned between the tab 74 and the arm 59 and between the tab 75 and the arm 60; whereby the aligned slots 80 and 81 embrace the ledge 27. A second substantially U-shaped laterally extending abutment 82 is arranged between the arms 59 and 60 adjacent to the lower front edges thereof and suitably secured in place by welding, or the like.

Further, the apparatus 10 comprises a motor driven impeller 90 arranged in the sump 28, an associated electric heating-unit 91 of the sheathed resistance conductor type carried by the bottom wall 19 of the vat 17 adjacent to the sump 28 and a washing fluid inlet spray device 92 carried by the top wall 18 of the vat 17; which elements

are utilized in the cyclic operation of the apparatus 10 as disclosed in the previously mentioned Walker application. Also, the side walls 20 and 21 of the vat 17 respectively carry baffle structures 93 and 94 which cooperates with baffle structure 95 carried by the door 33, whereby the front opening 23 of the doorway 22 is effectively closed by the door 33 when it occupies its closed position, notwithstanding the circumstance that there is no sealing gasket arranged between the doorway 22 and the door 33; all as disclosed in the previously mentioned Walker application. Further, the apparatus 10 comprises a dish-carrying receptacle or rack 96 that is movable through the doorway 22 into and out of the vat 17 when the door 33 occupies its open position; which rack 96 is provided with mounting mechanism respectively cooperating with the side walls 20 and 21 of the vat 17 and with the inner body sheet 36 of the door 33 to accommodate the movements noted; all as disclosed in the previously mentioned Walker application. This mounting arrangement mentioned comprises a front roller 97 carried by the lower central front portion of the rack 96 and cooperating with a substantially centrally disposed trackway 97' formed in the inner body sheet 36, as well as two laterally spaced-apart and rearwardly disposed lower rollers, not shown, carried by the rack 96 and respectively cooperating with two side trackways 98 and 99 carried by the inner body sheet 36 of the door 33. In accordance with this mounting arrangement the rack 96 is supported entirely by the side walls 20 and 21 of the vat 17 when it occupies its fully pushed-in position with respect to the vat 17; the rack 96 is supported entirely by the door 33 in its open position when it occupies its fully withdrawn position; and the rack 96 is supported jointly by the side walls 20 and 21 of the vat 17 and by the door 33 in its open position when it occupies intermediate positions with respect to its fully pushed-in position and its fully withdrawn position.

As previously noted the right-hand hinge mechanism 51 is disposed between the inner body sheet 36 and the outer body sheet 34 adjacent to the right-hand side of the door 33; while the left-hand hinge mechanism 52 is disposed between the inner body sheet 36 and the outer body sheet 34 adjacent to the left-hand side of the door 33. The right-hand hinge mechanism 51 and the right side trackway 98 are secured to the respective outer and inner surfaces of the inner body sheet 36 by three common securing devices 100; and, likewise, the left-hand hinge mechanism 52 and the left side trackway 99 are secured to the respective outer and inner surfaces of the inner body sheet 36 by three common securing devices 101. Preferably the securing devices 100 and the securing devices 101 are identical; for example, each of the securing devices 100 comprise a stud 102 positioned in a counter recess provided in the associated trackway 98 and a threaded shank 103 projecting into a connecting hole formed in the trackway 98, as well as a screw 104 provided with a hollow internally threaded barrel 105. The barrel 105 extends through aligned openings formed in the base 58 of the second hinge element 57 and in the body sheet 36; whereby the shank 103 is arranged within the barrel 105. When the head of the screw 104 is tightened the screw 104 and the stud 102 of the securing device 100 are drawn together securely clamping the trackway 98 to

the inner surface of the inner body sheet 36 and securely clamping the base 58 of the second hinge element 57 to the outer surface of the inner body sheet 36.

Considering now the operation of the door 33 in conjunction with the hinge mechanism 51 and 52, and denoting identical parts of the two mechanisms by the same reference characters, it will be understood that when the door 33 occupies its closed position the second abutments 82 carried by the arms 59 and 60 of the second hinge elements 57 disengage the first abutments 79 carried by the arms 63 and 64 of the bumper members 61, the arms 59 and 60 of the second hinge elements 57 are disposed above and forwardly with respect to the ledge 27, the ends of the locking pins 76 are disposed above the arcuate slots 77 and 78 formed in the arms 55 and 56 of the first hinge elements 53, and the saddles 69 disposed on the lower ends of the second hinge elements 57 straddle the upper surfaces of the pintles 68. Accordingly, the weight of the door 33 is carried primarily by the pintles 68 cooperating with the saddles 69 in the two hinge mechanisms 51 and 52, the lower end of the inner body sheet 36 is disposed rearwardly of and below the ledge 27, and the lower end of the outer body sheet 34 is disposed forwardly of and below the ledge 27. Moreover, the groove 41 provided on the lower end of the outer body sheet 34 receives the edge 42 provided on the panel 14; whereby the opening 23 in the doorway 22 is closed by the door 33 in order to prevent the escape from the vat 17 of washing fluid incident to the various washing steps that are cyclically performed; all as described in the previously mentioned Walker application.

As the door 33 is moved from its closed position toward its open position the saddles 69 ride around the cooperating pintles 68 in the two hinge mechanisms 51 and 52; whereby the door 33 is pivoted about its lower edge and around the ledge 27. More particularly, as the door 33 is moved towards its open position the arms 59 and 60 carried by the second hinge elements 57 move downwardly and rearwardly; whereby the ledge 27 enters the arcuate slots 80 and 81 formed in the bodies of the second hinge elements 57 and the second abutments 82 approach the first abutments 79. Also as the door 33 is moved toward its open position the ends of the locking pins 76 enter the associated locking slots 77 and 78 formed in the first hinge elements 53 of the hinge mechanisms 51 and 52 in order positively to prevent removal of the door 33 from the doorway 22 when the door 33 occupies its open position, as explained more fully hereinafter. When the door 33 occupies its open position the second abutments 82 engage the first abutments 79 and the ends of the locking pins 76 engage the bottom of the cooperating locking slots 77 and 78 formed in the arms 55 and 56 of the first hinge elements 53; whereby the door 33 is rigidly supported in its open position, the principal surface of the inner body sheet 36 occupying a substantially horizontal position at this time. Since the arms 59 and 60 of the second hinge elements 57 are disposed considerably forwardly of the ledge 27 and the pintles 68 and the locking pins 76, when the door 33 occupies its open position, the upper portion of the door 33 projecting out of the doorway 22 is adequately and rigidly supported eliminating any substantial cantilever action. Thus when the door 33 occupies its open position the rack 96 may be moved out of the vat 17 through 75

the doorway 22 into its fully withdrawn position wherein it is supported entirely by the door 33 without causing any substantial sagging of the door 33 even though the rack 96 is reasonably heavily loaded with dishes or other utensils. Since there is no substantial sagging of the door 33 in its open position even though it is reasonably heavily loaded, the trackways 97, 98 and 99 carried by the inner body sheet 36 of the door 33 remain in proper alignment with respect to the supporting facilities carried by the side walls 20 and 21 of the vat 17; whereby the rack 96 may be moved readily into and out of the vat 17 through the doorway 22 over the door 33 in its open position without interference.

In order to facilitate thorough cleaning of the interior of the vat 17 the door 33 may be completely removed from the doorway 22 when it occupies an intermediate position with respect to its closed and open positions by virtue of the circumstance that the hinge mechanisms 51 and 52 are of the disengageable type. More particularly, when the door 33 occupies its intermediate position the upper edge thereof has cleared the top flange 24 of the doorway 22 and the ends of the locking pins 76 have not ridden into the arcuate locking slots 77 and 78 formed in the arms 55 and 56 of the first hinge elements 53. Accordingly, at this time the saddles 69 may be disengaged from the supporting pintles 68 by lifting the door 33 upwardly and forwardly while it occupies its intermediate position, as illustrated in Fig. 4. After the interior of the vat 17 has been thoroughly cleaned the door 33 may be replaced in the doorway 22 by following a substantially reverse procedure while the door 33 occupies its intermediate upwardly and forwardly inclined position, as illustrated in Fig. 4.

Thus it will be understood that the door 33 may not be removed from the doorway 22 when it occupies its substantially closed position due to the interference of the upper edge thereof with the top flange 24 of the doorway 22. And, likewise, the door 33 may not be removed from the doorway 22 when it occupies its substantially open position due to the interlocking action between the ends of the locking pins 76 and the cooperating locking slots 77 and 78 formed in the arms 55 and 56 of the first hinge elements 53. Thus the door 33 may be removed from the doorway 22 only when it occupies substantially its intermediate position as explained above.

In view of the foregoing, it is apparent that there has been provided in washing apparatus of the front opening type improved hinge mechanism for mounting the door for movements between a substantially vertical closed position and a substantially horizontal open position; whereby there is no substantial sagging of the door when it occupies its open position even though it is reasonably heavily loaded. Moreover, this improved hinge mechanism permits ready removal of the door from the associated doorway when the door occupies an intermediate position with respect to its closed and open positions in order to facilitate thorough cleaning of the interior of the vat.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In dishwashing apparatus including a vat provided with a forwardly directed doorway terminating in a substantially vertical front opening, said doorway having a bottom flange and opposed side flanges, said bottom flange being provided with an upwardly directed ledge extending between said side flanges and terminating adjacent to said front opening, and a door; the combination comprising hinge mechanism including first and second hinge elements respectively secured to said bottom flange below and rearwardly of said ledge and interiorly of said doorway and to the lower portion of said door above said ledge and interiorly of said doorway for mounting said door for pivotal movements adjacent to the lower edge thereof about said ledge between a substantially vertical closed position and a substantially horizontal open position, and means including a first bumper member secured to said bottom flange exteriorly of said doorway and a second bumper member carried by the lower portion of said door exteriorly of said doorway for supporting the upper portion of said door projecting forwardly out of said doorway when said door occupies its open position, said second bumper member swinging around said ledge from an upper position disengaging said first bumper member into a lower position engaging said first bumper member when said door is moved from its closed position into its open position.

2. In cabinet structure including an upstanding doorway terminating in a substantially vertical front opening, said doorway having a bottom flange and opposed side flanges, said bottom flange being provided with an upwardly directed ledge extending between said side flanges and terminating adjacent to said front opening, and a door; the combination comprising hinge mechanism including first and second cooperating hinge elements for mounting said door within said doorway for movements with respect to said front opening between a substantially vertical closed position and a substantially horizontal open position, said first hinge element being secured to the upper surface of said bottom flange below and rearwardly of said ledge and said second hinge element being secured to the lower portion of said door above said ledge, said second hinge element projecting outwardly over said ledge when said door occupies its open position, a first bumper member secured to the lower surface of said bottom flange below and rearwardly of said ledge, and a second bumper member carried by said second hinge element, said second bumper member being disposed in an upper position forwardly of said ledge and disengaging said first bumper member when said door occupies its closed position and being disposed in a lower position rearwardly of said ledge and engaging said first bumper member when said door occupies its open position, said engaging bumper members supporting the upper portion of said door projecting forwardly out of said doorway when said door occupies its open position.

3. In cabinet structure including an upstanding doorway terminating in a substantially vertical front opening, said doorway having a bottom flange and opposed side flanges, said bottom flange being provided with an upwardly directed ledge extending between said side flanges and terminating adjacent to said front opening, and a door; the combination comprising hinge mechanism including first and second cooperating

hinge elements for mounting said door within said doorway for movements with respect to said front opening between a substantially vertical closed position and a substantially horizontal open position, first and second resilient pads respectively positioned upon the upper and lower surfaces of said bottom flange rearwardly of and below said ledge, said first hinge element being positioned upon said first pad, a first bumper member positioned upon said second pad, means for securing said first hinge element and said first bumper member and said first and second pads in assembled relation to said bottom flange, means for securing said second hinge element to the lower portion of said door above said ledge, said second hinge element projecting outwardly over said ledge when said door occupies its open position, and a second bumper member carried by said second hinge element, said second bumper member being disposed in an upper position forwardly of said ledge and disengaging said first bumper member when said door occupies its closed position and being disposed in a lower position rearwardly of said ledge and engaging said first bumper member when said door occupies its open position, said engaging bumper members supporting the upper portion of said door projecting forwardly out of said doorway when said door occupies its open position.

4. In cabinet structure including an upstanding doorway terminating in a substantially vertical front opening, said doorway having a bottom flange and opposed side flanges, said bottom flange being provided with an upwardly directed ledge extending between said side flanges and terminating adjacent to said front opening, and a door; the combination comprising hinge mechanism including first and second cooperating hinge elements for mounting said door within said doorway for movements with respect to said front opening between a substantially vertical closed position and a substantially horizontal open position, said first hinge element being secured to the upper surface of said bottom flange below and rearwardly of said ledge and said second hinge element being secured to the lower portion of said door above said ledge, said second hinge element projecting outwardly over said ledge when said door occupies its open position, a first bumper member secured to the lower surface of said bottom flange below and rearwardly of said ledge, a second bumper member carried by said second hinge element, said second bumper member being disposed in an upper position forwardly of said ledge and disengaging said first bumper member when said door occupies its closed position and being disposed in a lower position rearwardly of said ledge and engaging said first bumper member when said door occupies its open position, said engaging bumper member supporting the upper portion of said door projecting forwardly out of said doorway when said door occupies its open position, said hinge elements being disengageable to permit complete removal of said door from said doorway when said door occupies an intermediate position with respect to its open and closed positions, and means including interlocking parts respectively carried by said hinge elements for preventing disengagement thereof except when said door occupies its intermediate position.

5. In cabinet structure including an upstanding doorway terminating in a substantially vertical front opening, said doorway having a bottom flange and opposed side flanges, said bottom

11

flange being provided with an upwardly directed ledge extending between said side flanges and terminating adjacent to said front opening, and a door; the combination comprising hinge mechanism including first and second cooperating hinge elements for mounting said door within said doorway for movements with respect to said front opening between a substantially vertical closed position and a substantially horizontal open position, said first hinge element being carried by said bottom flange within said doorway rearwardly of said ledge and said second hinge element being carried by the lower portion of said door, one of said hinge elements carrying a pintle and the other of said hinge elements carrying a cooperating saddle permitting disengagement of said hinge elements and complete removal of said door from said doorway when said door occupies an intermediate position with respect to its open and closed positions, means including a locking pin carried by one of said hinge elements and a cooperating locking slot provided in the other of said hinge elements for preventing disengagement of said hinge elements except when said door occupies its intermediate position, said second hinge element projecting outwardly over said ledge when said door occupies its open position, a first bumper member carried by said bottom flange below said ledge, and a second bumper member carried by said second hinge element, said second bumper member being disposed in an upper position disengaging said first bumper member when said door occupies its closed position and being disposed in a lower position engaging said first bumper member when said door occupies its open position, said engaging bumper members supporting the upper portion of said door projecting forwardly out of said doorway when said door occupies its open position.

6. In cabinet structure including an upstanding doorway terminating in a substantially vertical front opening, said doorway having a bottom flange and opposed side flanges, said bottom flange being provided with an upwardly directed ledge extending between said side flanges and terminating adjacent to said front opening, and a door provided with inner and outer sheets secured together in spaced-apart relation; the combination comprising hinge mechanism including first and second cooperating hinge elements for mounting said door within said doorway for movements with respect to said front opening between a substantially vertical closed position and a substantially horizontal open position, the lower ends of said sheets being arranged in straddling relation with respect to said ledge so that when said door occupies its closed position the lower end of said inner sheet is disposed rearwardly of and below said ledge and the lower end of said outer sheet is disposed forwardly of and below said ledge, said first hinge element being secured to the upper surface of said bottom flange below and rearwardly of said ledge and said second hinge element being arranged between said sheets and secured to lower portion of said inner sheet above said ledge, said second hinge element projecting outwardly over said ledge when said door occupies its open position, a first bumper member secured to the lower surface of said bottom flange below and rearwardly of said ledge, and a second bumper member arranged between said sheets and carried by said second hinge element, said second bumper member being disposed in an upper position

12

tion forwardly of said ledge and disengaging said first bumper member when said door occupies its closed position and being disposed in a lower position rearwardly of said ledge and engaging said first bumper member when said door occupies its open position, said engaging bumper members supporting the upper portion of said door projecting forwardly out of said doorway when said door occupies its open position.

10 7. In cabinet structure including an upstanding doorway terminating in a substantially vertical front opening, said doorway having a bottom flange and opposed side flanges, said bottom flange being provided with an upwardly directed ledge extending between said side flanges and terminating adjacent to said front opening, and a door; the combination comprising hinge mechanism including first and second hinge elements respectively secured to said bottom flange
15 and to said door for mounting said door for pivotal movements adjacent to the lower edge thereof about said ledge between a substantially vertical closed position and a substantially horizontal open position, said first hinge element including a base and a pair of upwardly directed spaced-apart arms, a pintle extending between and secured to the arms of said first hinge element, said second hinge element including a base and a pair of forwardly directed spaced-apart arms, a saddle carried by the lower end of the base of said second hinge element and engaging said pintle, a bumper member secured to said bottom flange and including a base and a pair of downwardly directed spaced-apart arms, a first
20 abutment extending between and secured to the arms of said bumper member, and a cooperating second abutment extending between and secured to the arms of said second hinge element, said abutments engaging and supporting the upper portion of said door projecting forwardly out of said doorway when said door occupies its open position.

8. In cabinet structure including an upstanding doorway terminating in a substantially vertical front opening, said doorway having a bottom flange and opposed side flanges, said bottom flange being provided with an upwardly directed ledge extending between said side flanges and terminating adjacent to said front opening, and
45 a door; the combination comprising hinge mechanism including first and second hinge elements respectively secured to said bottom flange and to said door for mounting said door for pivotal movements adjacent to the lower edge thereof
50 about said ledge between a substantially vertical closed position and a substantially horizontal open position, said first hinge element including a base and a pair of upwardly directed spaced-apart arms, a pintle extending between and secured to the arms of said first hinge element, said second hinge element including a base and a pair of forwardly directed spaced-apart arms, a saddle carried by the lower end of the base of
55 said second hinge element and engaging said
60 pintle, a bumper member secured to said bottom flange and including a base and a pair of downwardly directed spaced-apart arms, a first abutment extending between and secured to the arms of said bumper member, a cooperating second
65 abutment extending between and secured to the arms of said second hinge element, said abutments engaging and supporting the upper portion of said door projecting forwardly out of
70 said doorway when said door occupies its open
75 position, said saddle being disengageable from

said pintle to permit complete removal of said door from said doorway when said door occupies an intermediate position with respect to its open and closed positions, the arms of said first hinge element having aligned locking slots formed therein, and a locking pin extending between and secured to the arms of second hinge element, said locking pin entering said locking slots and preventing disengagement of said saddle and said pintle when said door is moved from its intermediate position toward its open position. 10
